(57) **CLAIM**

The ornamental design for a bracelet, as shown and described.

DESCRIPTION

FIG. 1 is a perspective view of a bracelet showing the new design;

FIG. 2 is a front view thereof;

FIG. 3 is a top view thereof;

FIG. 4 is a bottom view thereof;

FIG. 5 is a left side view thereof;

FIG. 6 is a right side view thereof; and,

FIG. 7 is a back view thereof.

The spaced lines shown in FIGS. 1-7 are intended to illustrate surface shading for illustrative clarity only, and do not themselves form any part of the claimed design.

The broken lines shown in FIGS. 1 through 7 illustrate portions of the bracelet that form no part of the claimed design.

1 Claim, 3 Drawing Sheets

FIG. 1
